INVENTOR

Clarence D. Platt,

BY

R. S. Dwyer, ATTORNEY

UNITED STATES PATENT OFFICE.

CLARENCE D. PLATT, OF BRIDGEPORT, CONNECTICUT.

INCLOSED ELECTRIC SWITCH.

Application filed February 3, 1923. Serial No. 618,656.

To all whom it may concern:

Be it known that I, CLARENCE D. PLATT, a citizen of the United States of America, and residing at Bridgeport, in the county of 5 Fairfield and State of Connecticut, have invented new and useful Improvements in Inclosed Electric Switches, of which the following is a specification.

The main object is to provide a simple, 10 practical construction in which protected fuses may be readily installed or replaced in a perfectly safe manner.

Another object is to so construct such a device that it may be readily assembled and 15 wired.

Another object is to provide particularly simple means for preventing access to the live parts of the switch even when the fuse plug sockets are exposed.

Another object is to provide simple and 20 practical means for interlocking a movable part of the switch with a sliding cover.

The accompanying two sheets of drawings 25 show one form of construction embodying improvements of my invention.

Figure 1 is a plan view of a construction embodying improvements of my invention, the interior parts being shown dotted.

Fig. 2 is a longitudinal sectional view 30 showing the switch in the closed circuit position and the cover slide closed.

Fig. 3 is a similar sectional view showing the switch in the open circuit position and the cover slide open.

Fig. 4 is a transverse sectional view.

Fig. 5 is a perspective view of the slide and interlocking part.

The box or receptacle may be of any suitable form having a body 7 and a cover 8 40 which will usually have a hinge connection such as 9 and some form of catch or lock to hold the cover closed.

The switch proper is carried by a base 10 formed of insulating material. The stationary posts 11 suitably secured to the base 45 support the swinging blades 12, the movable ends of which are adapted to engage the clips 13. The circuit terminals 14 are secured to the clips 13. The opposite end 50 of the base 15 is preferably much higher and provided with recesses for the fuse plug sockets of any suitable form. In the form shown these sockets have threaded shells 16 connected by strips 17 which extend through 55 the base and are provided with circuit ter-

minals 18. The central socket contacts 19 may be in the form of screws connected to the strips 20 in the back of the base which in turn are connected to the supporting posts 11. In the form shown the blades 12 are 60 connected by an insulating cross-bar 21 and adapted to be operated by the crank member 22 pivoted in the body of the box and having an external handle 23. The cross-bar may be connected to the operating member 22 65 in any suitable manner for instance by means of a bracket or arm 24.

The base is provided with an insulating wall 25 which projects outwardly between the fuse plug sockets and the switch proper. 70 The base is somewhat narrower than the box so that channels 26 are left at the sides through which conductors may be led to the circuit terminals 18 if desired.

A cover is provided with an opening 27 to 75 permit access to the fuse plug sockets. This opening is normally closed by the slide 28 which is suitably guided in the cover, for instance by means of a flanged member 29 which forms in conjunction with the cover a 80 guideway or groove. The slide may be provided with an operating knob or handle 30 for convenience. When the slide is open as shown in Fig. 3, access may be had to the fuse plug sockets for inserting, examining, or 85 removing the fuse plugs. It will be noted, however, that the wall 25 entirely prevents access to the switch proper or the circuit terminals.

In order to prevent the slide from being 90 opened when the switch is in the closed circuit position, I have provided a member 31 which is secured to the slide and has a hook-like member 32 which normally engages the operating member 22 as shown in Figure 2. 95 It will be seen from this figure that with the switch in the closed circuit position the hook 32 engaging the operating member 22 prevents the slide from being moved to the right. The member 31, however, is cut away 100 at 33 so as to permit the operating member to be swung to the left as shown in Fig. 2 for the purpose of opening the switch. When the switch has been opened in the position shown in Fig. 3, the slide may be 105 pushed to the right so as to permit access to the fuse plug sockets through the opening 27. The member 31 is provided with an edge or shoulder 34 which when the parts are in the position of Fig. 3 stands in the 110

way of the operating member 22 and thus makes it impossible to close the switch while the fuse plug sockets are exposed. Although this construction is very simple and inexpensive it is very practical and effective.

It will be noted that all of the wire terminals are located in the protected end of the box, thus there are no wire attaching means accessible through the cover-opening 10 where the cover is closed.

I claim:

1. In an inclosed switch, a box having an opening, a shutter for said opening, a switch mounted in said box including fuse plug 15 sockets accessible through said opening and movable blades in the other end of said box, an operating member for said blades and an interlocking bar carried by said shutter having a hook engaging said operating member to prevent the operation of said shutter except the switch is fully open and having a portion for engaging said member to prevent movement of said operating member except said shutter is closed.

2. In an inclosed switch, a box body and cover having an opening, a shutter for said opening, a movable switch member in said box, an operating member therefor, a bar carried by said shutter having a hook engaging said operating member, said bar being constructed to permit the movement of said operating member when said shutter is closed, to permit movement of said shutter when the switch is open, and to prevent 35 closing movement of the switch when the shutter member is open.

3. In an inclosed switch, a box body and cover, said cover having an opening, an insulating base mounted in said box body, a movable switch member mounted on one end of said base, fuse contacts in the other end of said base in register with said opening, said base having an integral projecting barrier located between said movable switch member and said fuse contacts and said fuse contacts having means on the opposite side of said barrier for connection with said movable switch member and with an electric circuit respectively.

4. In an inclosed switch, a box body, a cover therefor having an opening, an insulating block mounted in said body, a movable switch member carried by one end of said block, circuit terminals mounted on said end of said block, fuse plug sockets in the opposite end of said block, a projecting insulating wall carried by said block between said fuse plug sockets and said movable switch member, and circuit terminals carried by said block between said movable switch member and said wall.

5. As an article of manufacture, an insulating switch block, circuit terminals and switch clips mounted on one end of said

block, fuse plug sockets mounted in the opposite end of said block, hinged switch members connected to said block between said fuse plug sockets and said clips, circuit terminals carried by said block between said hinged switch members and said fuse plug 65 sockets and connected to the latter, means of connection between said fuse plug sockets and said hinged switch members, and an insulating wall projecting from said block between said last mentioned circuit terminals 75 and said fuse plug sockets.

6. In an inclosed switch, a box having an opening, a shutter for said opening, a switch mounted in said box including fuse plug 80 sockets accessible through said opening and movable blades in the other end of said box, an operating member for said blades, an insulating barrier between said blades and sockets and an interlocking member carried by said shutter having a hook engaging said 85 operating member to prevent the operation of said shutter when the switch is closed and having a portion for engaging said member to prevent movement of said operating member when said shutter is open. 90

7. In an inclosed switch, a box body and cover, said cover having an opening, an insulating block mounted in said box body, a movable switch member and circuit terminals mounted on one end of said block, fuse 95 contacts mounted in the other end of said block in line with said opening and connected respectively to said movable switch member and to one of said terminals, said block having an integral projecting wall located between said fuse contacts and said circuit terminals. 100

8. As an article of manufacture, an insulating switch block higher at one end than the other, circuit terminals and switch clips mounted on the lower end of said block, fuse plug sockets mounted in the opposite higher end of said block, hinged switch members connected to said block between said fuse plug sockets and said clips, circuit terminals 105 carried by said block between said hinged switch members and said fuse plug sockets and connected to the latter, means of connection between said fuse plug sockets and said hinged switch members, and an insulating wall projecting from said block between said last mentioned circuit terminals 110 and said fuse plug sockets.

9. In an inclosed switch, a box body, a cover therefor having an opening, an insulating block mounted in said body leaving wire channels on opposite sides, a movable switch member carried by one end of said block, circuit terminals mounted on said end of said block, fuse plug sockets in the 120 opposite end of said block, a projecting insulating wall carried by said block between said fuse plug sockets and said movable

switch member, and circuit terminals carried by said block between said movable switch member and said wall.

10. In an inclosed switch, a box body and a cover therefor having an opening, a movable shutter for said opening, a movable switch member in said box, an operating member therefor, a barrier between said member and said opening, a bar carried by

said shutter having a hook engaging said operating member, said bar being constructed to permit the movement of said operating member when said shutter is closed, to permit movement of said shutter when the switch is open, and to prevent closing of said switch when the shutter is open.

CLARENCE D. PLATE
